Specification for Design.

Patented Apr. 13, 1920.

Application filed December 23, 1918. Serial No. 268,106. Term of patent 14 years.

To all whom it may concern:

Be it known that I, PETER F. CAMPBELL, a citizen of the United States of America, residing at Vinal Haven, in the county of Knox and State of Maine, have invented a new, original, and ornamental Design for Tobacco-Pipes, of which the following is a specification, reference being had to the accompanying drawings, forming part thereof.

In the drawings, Figures 1, 2, 3, and 4 are top, side, front end, and bottom views, respectively, showing my new design.

I claim:

The ornamental design for a tobacco pipe, as shown.

PETER F. CAMPBELL.
